(57) **CLAIM**

The ornamental design for a bracket, as shown and described.

DESCRIPTION

FIG. 1 is a top, front, left perspective view of a bracket, showing our new design in the context of a wheelchair; FIG. 2 is a top, front, and left perspective view of the bracket;

FIG. 3 is a left elevational view of the bracket; FIG. 4 is a right elevational view of the bracket; FIG. 5 is a front elevational view of the bracket; FIG. 6 is a rear elevational of the bracket; FIG. 7 is a top plan view of the bracket; FIG. 8 is a bottom plan view of the bracket; FIG. 9 is a left side cross-sectional view taken through line 9-9 of FIG. 5; and, FIG. 10 is a right side cross-sectional view taken through line 10-10 of FIG. 5.

The broken lines shown in the drawings are for the purpose of illustrating unclaimed portions of the bracket or the environment and form no part of the claimed design. In a preferred embodiment, the nature of this product is as a bracket for a knee adductor assembly for attachment to a wheelchair.
